MEANS FOR LINE JUSTIFICATION

Robert E. Paris, New York, N. Y.

Application August 28, 1934, Serial No. 741,798

4 Claims. (Cl. 88—24)

This invention relates to a method of line justification for typewritten matter, and photographic means for carrying such method into operation.

5 In the past when photo mechanical reproduction of typewritten data has been tried, line justification, that is, the proper spacing of the characters to make the length of all lines uniform, has been attained in many different ways, 10 such as; manual spacing by the operator on the typewriter, typing on tape and cutting to proper length and mounting, typing on stretchable paper, cutting into strips and mounting, etc. All these and other methods have been slow and 15 require considerable time for preparation of the copy.

One of the objects of the present invention is to effect line justification of typewritten or the like matter, without the necessity of doing anything to the original record in the way of cutting, stretching, or the like.

Another object is to produce a device for photographic reproduction of typewritten or the like matter, having means for relatively adjusting the plate or film and the typed sheet, so as to compensate for the variation of line lengths on the sheet, and make all reproduced lines of even length.

Another object is to produce a device for effecting concomitant operation of the plate or film, and the work sheet.

Other objects will appear from the following detailed description, and appended claims. One form of device for carrying my invention into effect is illustrated in the accompanying drawings, in which:

Fig. 1 is a side elevation of a device for carrying my invention into practice.

Fig. 2 is a top plan view of the same.

40 Fig. 3 is a fragmentary detail perspective view of the copy holder, film, and the means for advancing the two concomitantly.

Fig. 4 is a detail perspective view of the copy holder and its mask.

45 Fig. 5 is an enlarged fragmentary detail perspective view showing the copy holder and associated parts.

Like characters of reference refer to like parts in all views.

50 Referring to the drawings in detail, 10 represents the framework of the machine, which may be of any suitable construction to support the working parts of the machine. Mounted on the framework 10 is a camera 11, the lens board 12 being indicated at 12. The lens board 12 is

secured to a rod 13 which extends across the machine, and near its ends rests in bifurcations in levers 14 pivoted at 15 to brackets 16 secured to the framework of the machine. Springs 17 tend constantly to move the lens board toward the right in Fig. 1. The lower ends of levers 14 carry anti-friction rollers 18, which ride on the curved surfaces of cams 19 fixed to a shaft 20 having bearings in the machine framework. 5

Inside the camera is supported in any well known manner, a supply roll 21 (Fig. 3) carrying photographic film, sensitized paper or the like indicated at 22. The film 22 is fed down in back of a mask 23, about a feed roll 24 to the receiving roll 25. Feed roll 24 is fixed on a shaft 26 which extends through the side of the camera, and carries a beveled gear 27 meshing with a gear 28 fixed to a stub shaft 29 having its bearing in a suitable bracket. Slidably mounted on the lower end of shaft 29 is a clutch member 30 which may be raised and lowered by a handle 31 (Fig. 1).

Fixed to the machine frame, and arranged angularly with respect to the camera 11, are slotted rails 32 (Fig. 2), in which brackets 33 are arranged to ride. Carried by brackets 33 is a frame 34 which carries a removable mask 35. The aperture in this mask is large enough to expose only one line of typewriting at a time. The right hand end of this aperture may be provided with a scale indicating letter-spaces. The armature of this mask is in optical alignment with the aperture in mask 23. Slidably supported in the frame 34 is a copy-holder formed of a back portion 36 to which are hinged side flaps or clamping strips 37. Portions of soft rubber or felt are shown at 38 as set into the face of member 36 to co-act with strips 37 for gripping the paper 37'. 25 30 35

Fastened to the lower edge of the copy-holder and extending downwardly therefrom is a rack bar 39, the teeth of which mesh with a long pinion 40 fast on a shaft 41 having bearings in the main frame, or in brackets attached thereto. Fast on shaft 41 is a bevel gear 42 which is in mesh with a gear 43 fast on a stub shaft 44 in axial alignment with stub shaft 29. Fixed on the upper end of stub shaft 44 is a clutch member 45. Shaft 41 is disposed parallel with the angular edges of rails 32. 40 45 50

Pivottally attached to brackets 33 are respective links or push rods 46, the opposite ends of rods 46 being pivotally connected to a U shaped frame 47 having its legs pivotally secured to the main framework. Secured to the middle of 55

frame 47 is a handle 48 by which the frame may be conveniently rotated about its pivots. Fixed to one leg of frame 47 is an indicator 49 which traverses a scale plate 50, the graduations 5 on which are arranged to correspond with those on the mask 35. A link 51 connects frame 47 to a cam 19 (Fig. 1).

The method of justifying is as follows:—Successive photographs of successive lines of type-10 writing are made the distance between the copy and the sensitive plate, being varied according to the length of the typewritten line, so as to make all photographic lines of equal length, the left-hand letter of the copy being arranged to always 15 fall on the same vertical line of the plate.

The means above described for carrying this method into effect operates as follows:—First, the film 22 is placed in the camera. Then the copy-holder 36—37 is raised, the clutch 30 being dis-20 connected. The sheet to be copied is placed against portion 36 and clamped there by strips 37. The copy-holder is lowered until the first line of the typewriting is visible through the opening in mask 35. The frame 34 is moved to the right or 25 left in Fig. 1, according to the reading of the last letter of the line on the scale on mask 35. This movement is accomplished by movement of handle 48, the amount of movement being indicated by moving indicator 49 over scale 50 until it corre-30 sponds with the reading of the scale on mask 35. The angle of rails 32 is such as to keep the left hand letter space of the copy always in the same vertical line of photographic reproduction on the film or plate 22. The movement of frame 47 35 causes link 51 to effect movement of cams 19 so as to move the lens board 12 accordingly, the con- tour of cams 19 being such as to give the correct focus. Lever 31 is now shifted so as to clutch members 30 and 45. The photograph of line "1" 40 is now taken. The copy is now raised to expose line "2". During this operation rack 39 turns pinion 40 and shaft 41, which causes gear 42 to turn gear 43, and, as shafts 44 and 29 are clutched together, causes gear 28 to turn gear 27, whereby 45 the film or plate 22 is advanced one line space.

The reading on the scale at the aperture in mask 35 is again taken, handle 48 is moved until indicator 49 is in a corresponding position on scale 50, and the next photograph is taken, etc.

It is, of course, understood that the camera, or parts of it, could be moved instead of the copy, and that the device if stood on its side would bring the left-hand side of the copy always in the same horizontal (instead of vertical) plane on the 55 film or plate. It will, of course, be understood that 22 represents any sort of photographic material, whether it be film, paper, plate, or what not.

While I have described what I consider to be a highly desirable embodiment of my invention, it 60 is obvious that many changes in form could be made without departing from the spirit of my

invention, and I, therefore, do not limit myself to the exact form herein shown and described, nor to anything less than the whole of my invention as hereinbefore set forth, and as hereinafter claimed.

What I claim is:

1. A machine of the character set forth includ-10 ing a camera, a copy-holder for holding copy in- cluding unjustified copy lines, means for moving the camera and copy-holder relatively for in- creasing and decreasing the distance therebe-20 tween, and means for automatically effecting lat- eral adjustment of the camera and copy-holder according to the relative movement effected by the first said means in such manner as to position the left-hand end of the copy line so that it will always be photographed in the same vertical plane on a photographic plate in said camera, and means for concomitantly advancing the copy and the plate.

2. A machine of the character set forth includ-25 ing a camera, a copy-holder, a scaled mask asso- ciated with said copy-holder for indicating to the operator the amount of justification necessary, means for causing relative movement between said camera and copy-holder, means for automatically effecting lateral adjustment of the camera and copy-holder according to the relative movement effected by the first said means in such manner as to position the left-hand end of the 30 copy line so that it will always be photographed in the same vertical position on a photographic plate in said camera, and a second scale proportioned to the scale on said mask for indicating the extent of such movement in terms of the scale 35 on said mask.

3. In a machine of the character set forth, the combination of a copy holder, a light-sensitive plate, a train of gearing between said copy holder and said plate whereby line-feeding of one will 40 automatically effect line-feeding of the other, said train including a diagonally arranged shaft having a slidable connection with said copy holder, and means for moving the copy holder toward and from the plate and for automatically moving the copy holder transversely for keeping the left-45 hand margin of the copy in constant justification.

4. In a machine of the character set forth, the combination of a copy holder, a light-sensitive plate, a train of gearing between said copy holder and said plate whereby line-feeding of one will 50 automatically effect line-feeding of the other, said train including a diagonally arranged shaft having a slidable connection with said copy holder and also including a clutch for connecting and disconnecting said copy holder and plate, and means for moving the copy holder toward and from the plate and for automatically moving the copy holder transversely for keeping the left-55 hand margin of the copy in constant justification. 60

ROBERT E. PARIS.
